UNITED STATES PATENT OFFICE.

RAFFAELE PAROSELLI, OF JERSEY CITY, NEW JERSEY.

SAFETY DEVICE FOR ELEVATORS.

SPECIFICATION forming part of Letters Patent No. 606,489, dated June 28, 1898.

Application filed March 19, 1898. Serial No. 674,481. (No model.)

To all whom it may concern:

Be it known that I, RAFFAELE PAROSELLI, of Jersey City, in the county of Hudson and State of New Jersey, have invented a new and Improved Safety Device for Elevators, of which the following is a full, clear, and exact description.

My invention relates to an improvement in safety devices for elevators designed to stop the elevator quickly and securely in case of breakage of the suspending-cables and including also a mechanism by which the elevator-cage may be safely lowered to a landing if it becomes stopped between floors.

My invention consists of the novel construction hereinafter described and claimed.

Reference is to be had to the accompanying drawings, forming a part of this specification, in which similar characters of reference indicate corresponding parts in all the views.

Figure 1 is an elevation, partially in section, on the line 1 1 in Fig. 3, showing the elevator-cage in the upper portion of the elevator-well. Fig. 2 is a similar view showing in operation the device for lowering the cage. Fig. 3 is a plan view showing the mechanism for lowering the elevator-cage. Fig. 4 is a horizontal section on the line 4 4 in Fig. 1. Fig. 5 is a sectional elevation on the line 5 5 in Fig. 4, and Fig. 6 is a detail elevation of the clutch mechanism for stopping the cage.

In the drawings, A represents the guides which are usually provided to control the position of the cage in the elevator-well. The guides may be of any ordinary construction, but are preferably made with their outer edge surfaces plain. As herein shown, one of these guides is placed at each corner of the cage.

The elevator-cage is constructed in two principal parts—the cage proper and a casing which surrounds the cage and engages the guides A. This outside casing is formed of the vertical bars B, one located at each corner and connected at top and bottom by the cross-bars B' and B². These cross-bars are provided with blocks B³, which embrace the edges of the guides A. Between the vertical posts or bars B, near their upper ends, are located the eccentrics C, pivoted upon the pins C' and each having an arm projecting toward the center of the cage and provided with a longitudinal slot C², adapted to embrace a pin d in a block

D³, mounted upon the upper end of the cage, which latter is constructed in any suitable manner. As herein shown, it comprises the vertical bars D², connecting the upper floor D and the lower floor D'. To the upper floor are connected the blocks D³, which support the ends of the pins d, which engage the eccentrics. The cage and the casing are mounted so as to have relative vertical movement. It is obvious that when the cage moves downward relative to the casing the eccentrics will be rotated upon their pivots so as to force the eccentrics outward against the edges of the guides A, and thus to bring sufficient pressure upon the guides to hold the cage against dropping.

The suspending-cables F, which run upon a grooved pulley F' at the top of the elevator-well, are attached to the cage by a yielding connection, which is formed in the following manner: Upon the upper floor D are mounted two staples E', within which is placed a cross-bar E, and the cables are attached directly to this cross-bar. The cross-bar is attached to the upper floor D of the cage by means of springs e, which tend to hold the cross-bar down close to the cage and out of contact with the upper ends of the staples E'. When the cables F are drawn upon, the weight of the cage is such that it will overcome the stress of the springs and permit the cross-bar E to engage the upper ends of the staples, as shown in Fig. 1. When, however, the cables F are broken, the springs e will immediately draw the cross-bar close to the upper floor D or into the position shown in Fig. 2.

Beneath the lower floor D' is a shaft H⁵, supported in brackets h, attached to the undersurface of said floor. The shaft has fixed thereto one or more eccentrics H⁶, as is clearly shown in Figs. 1, 2, and 5. Upon the same shaft is keyed a gear-wheel H⁴, meshed with an idler-pinion H³, and to this idler-pinion is fixed a gear-wheel H², which meshes with a pinion H', mounted upon a short shaft which extends within the cage. Upon the inner end of this shaft is fixed a crank H, provided with a handle h', adapted to be engaged from the inside of the cage, so as to slightly rotate the eccentric H⁶ by means of the train of gearing. The eccentrics engage with a flooring B⁴, mounted upon the cross-bars B² of the

outer casing. Between the cross-bars B^2 of this casing and the lower floor D' extend springs I , which tend to draw the two floors toward each other; but this tendency is resisted by the eccentrics H^6 when in the position shown in Fig. 1. The two parts are separated a sufficient distance to prevent the working of the clutch-eccentrics C by rotating the eccentrics H^6 through the means of the crank H .

The crank H is provided with a notch in its upper end adapted to be engaged by a pin g upon one end of a lever G^3 . This lever is mounted upon a standard G^4 within the cage or is otherwise mounted upon the frame of the cage and is connected at its opposite end to a rod G^2 , which extends upward above the upper end of the cage. At its upper end the rod G^2 is connected to a spring G^1 , which acts to raise the rod and hold the pin g in engagement with the notch in the crank H . To the upper end of the rod G^2 is pivotally connected a bar G , which lies upon the upper floor D and extends beneath the cross-bar E . If the cross-bar E is allowed to be drawn down by the action of the springs e , as will happen when the suspending-cables F are broken, the bar G will be depressed and thus cause the pin g to be raised from engagement with the crank H , and the weight in the cage and the action of the springs I will cause a downward movement of the cage relative to the casing. This will throw the clutch-eccentrics C outward, so as to engage the guides A and stop the descent of the cage. The greater the weight of the cage and its load the harder the eccentrics will be forced outward into engagement with the guides. The power applied to restrain the cage is thus proportionate to the weight thereof.

The crank-handle h , being within the cage, may be operated by the attendant so as to release the clutch-eccentrics C at any time. It might be possible by this means to release the pressure sufficiently to allow the cage to slide downward without any danger to the occupants. To make this descent perfectly safe, however, I have provided another mechanism. At the top of the elevator-well, upon bars A' , which extend from one guide to another, is mounted a governor. Upon the bars A' are fixed two vertical plates M , which have side extending bars m , in which is journaled the shaft Q of a fan or rotating blade Q' . The shaft Q is connected by means of a bevel-pinion P^4 at its lower end to a bevel-pinion P^3 , mounted upon a shaft carrying a spur-pinion P^2 , engaging with a gear P' upon an idler-shaft carrying a pinion P , engaging with a gear-wheel K^2 upon a shaft K' . The gear-wheel K^2 is secured to the shaft K' by means of a ratchet-wheel L and its dog, so that the gear-wheel is secured to the shaft when rotated in one direction, but free to move thereon while rotated in the other direction.

Upon the shaft K' is a wheel K , which is

secured to the shaft K' and rotates therewith. The construction described may be reversed—that is, the wheel K may be mounted loosely upon the shaft and the gear-wheel K^2 be keyed to the shaft. In either case, one or the other wheel is secured to the shaft by means of the ratchet-wheel L . As herein shown, the wheel K is a plain pulley, having projecting pins k on its periphery and adapted to engage a belt J . For this purpose the belt is provided with holes suitably spaced to engage the pins k . Normally the belt J is not attached to the cage, but hangs loosely, as shown in Fig. 1. The belt after leaving the wheel K passes beneath a roller or bar N and then over a pulley O and between said pulley and a guide-link O^2 . At this point the belt is held upon the pulley O by means of a spring O' , so as to increase the amount of friction of the belt upon the pulley, the object being to retard the belt enough to insure a firm engagement with the wheel K . When the clutch mechanism has been thrown into operation and the cage stopped, the belt J is drawn down and attached to the cage, as shown in Fig. 2. For conveniently attaching the belt two bars E^2 are shown as extending upwardly from the cross-bar E , said bars E^2 being connected together by pins E^3 . The upper pin E^3 is adapted to receive the lower end of the belt J .

In case of accident which results in stoppage of the cage the belt J is brought down and attached to the upper pin E^3 . When thus secured, the clutch-eccentrics C are released by means of the crank H until the cage begins to drop. The connection of the belt J to the governing device will result in rapidly rotating the vane Q' . As a consequence the fall of the cage is limited in speed and cannot attain a speed which will be dangerous. When the cage reaches a position near a landing, the crank H is released by pulling upwardly on the lever G^3 , thus raising the pin g from the notch in the crank. The clutch mechanism is thus thrown into operation to stop the cage, and the occupants may then leave the cage in the usual manner.

By this means one of the discomforts attendant upon the use of the ordinary elevator safety devices is obviated.

Having thus described my invention, I claim as new and desire to secure by Letters Patent—

1. An elevator, comprising a cage formed in two parts adapted to have relative vertical movement, a locking device adapted to normally restrain the movement of said parts in one direction, a guide-clutching mechanism actuated by the relative movements of the parts of the cage, a suspension device for the cage, having a limited yielding action, and a trip for the locking device, actuated by the recoil of the suspension device when the strain on the latter is relieved, substantially as described.

2. An elevator, comprising a cage formed in two parts adapted to have relative vertical movement, springs supporting one of said parts from the other, a locking device adapted to normally restrain the action of the springs, a guide-clutching mechanism actuated by the relative movement of the parts of the cage, a spring-influenced suspension device for the cage, having a limited yielding action, and a trip for the locking device, actuated by the recoil of the suspension device when the strain on the latter is relieved, substantially as described.

3. An elevator, comprising a cage formed in two parts adapted to have relative vertical movement, a locking device adapted to normally restrain the movement of said parts in one direction, clutch-dogs connected to the parts of the cage and actuated to engage the elevator-guides by the relative movements of the parts of the cage, a suspension device for the cage, having a limited yielding action, and a trip for the locking device actuated by the recoil of the suspension device when the strain on the latter is relieved, substantially as described.

4. An elevator, comprising a cage formed in two parts adapted to have relative vertical movement, a locking device adapted to normally restrain the movement of said parts in one direction, eccentrics pivoted upon one part of the cage and having arms connected to the other part, whereby the eccentrics are forced into engagement with the elevator-guides by the relative vertical movement of the parts of the cage, a suspension device for the cage, having a limited yielding action, and a trip for the locking device, actuated by the recoil of the suspension device when the strain on the latter is relieved, substantially as described.

5. An elevator, comprising a cage formed in two parts adapted to have relative vertical movement, springs supporting one of said parts from the other, a locking device adapted to normally restrain the action of the springs, eccentrics pivoted upon one part of the cage and having arms connected to the other part, whereby the eccentrics are forced into engagement with the elevator-guides by the relative movement of the parts of the cage, a spring-influenced suspension device for the cage, having a limited yielding action, and a trip for the locking device actuated by the recoil of the suspension device when the strain on the latter is relieved, substantially as described.

6. An elevator, comprising a cage formed in two parts, a main cage and an auxiliary frame adapted to have relative vertical movement, a suspension connection between the main cage and the auxiliary frame, eccentric clutch-dogs pivoted upon the auxiliary frame and adapted to engage the elevator-guides, said dogs having operative connection with the main cage, a lock adapted to restrain the movement of the parts of the cage, and a trip for the

lock held out of action by the strain upon the suspension connection, substantially as described.

7. An elevator, comprising a cage formed in two parts, a main cage and an auxiliary frame adapted to have relative vertical movement, a suspension connection between the main cage and the auxiliary frame, eccentric clutch-dogs pivoted upon the auxiliary frame and adapted to engage the elevator-guides, said dogs having operative connection with the main cage, an eccentric pivoted upon one part of the cage and engaging the other, to hold the two separated and the clutch-dogs in inoperative position, a lock normally holding the parts in said position, springs connecting the two parts of the cage and acting in opposition to the eccentrics to throw the dogs into action, and a trip for the lock, held out of action by the strain upon the suspension connection, substantially as described.

8. An elevator, comprising a cage formed in two parts, a main cage and an auxiliary frame adapted to have relative vertical movement, a suspension connection between the main cage and the auxiliary frame, eccentric clutch-dogs pivoted upon the auxiliary frame and adapted to engage the elevator-guides, said dogs having operative connection with the main cage, an eccentric pivoted upon one part of the cage and engaging the other part to hold the two separated and the clutch-dogs in inoperative position, a crank within the cage having a rotative connection with said eccentric, a lock for said crank, springs connecting the two parts of the cage and acting in opposition to the eccentric to throw the dogs into action, and a trip for the lock, held out of action by the strain upon the suspension connection, substantially as described.

9. A lowering device for elevators, comprising a governor fixed at the top of the elevator-well and having a wheel adapted to receive a flexible connector, a flexible connector passing over said wheel and adapted to be connected with the cage to support it, means for freeing the elevator-cage and for locking it in the well, at will, and positive means by which the belt is prevented from slipping on the wheel, substantially as described.

10. A lowering device for elevators, comprising a governor fixed at the top of the elevator-well and having a wheel adapted to receive a flexible connector, a flexible connector passing over said wheel and adapted to be connected with the cage to support it, means for freeing the elevator-cage and for locking it in the well, at will, and a friction device acting upon the belt before it reaches the wheel, substantially as described.

11. In a lowering device for elevators, a governor fixed at the top of the well and having a wheel adapted to receive a flexible connector, a ratchet connection between said wheel and the governor mechanism permitting said wheel to run free in one direction, a flexible connector passing over said wheel, and adapt-

ed to be connected with the cage to support it, and means for freeing the elevator-cage and for locking it in the well, at will, substantially as described.

5 12. In a lowering device for elevators, a governor fixed at the top of the elevator-well and comprising a revolving vane, a wheel and multiple gearing between the vane and wheel, said wheel being adapted to receive a flexible connector, a flexible connector passing over said wheel and adapted to be connected with the cage to support it, and means for freeing the elevator-cage and for locking it in the well, at will, substantially as described.

10 13. In a lowering device for elevators, a gov-

ernor fixed at the top of the elevator-well and comprising a revolving vane, a wheel, and multiple gearing between them, said wheel being adapted to receive a flexible connector, a flexible connector passing over said wheel and adapted to be connected with the cage to support it, means for freeing the elevator-cage and for locking it in the well, at will, and a friction device acting on the belt before it reaches the wheel, substantially as described. 25
